(57) **CLAIM**

The ornamental design for a non-fraying line cover, as shown and described.

DESCRIPTION

FIG. 1 is a top, front perspective view of a non-fraying line cover showing my new design;
FIG. 2 is a top plan view thereof;
FIG. 3 is a bottom plan view thereof;
FIG. 4 is a front elevational view thereof;
FIG. 5 is a rear elevational view thereof;
FIG. 6 is a left side elevational view thereof, the right side elevational view being a mirror image thereof;
FIG. 7 is a top, front perspective view of a second embodiment of a non-fraying line cover showing my new design;
FIG. 8 is a top plan view thereof;
FIG. 9 is a bottom plan view thereof;
FIG. 10 is a front elevational view thereof;
FIG. 11 is a rear elevational view thereof; and,
FIG. 12 is a left side elevational view thereof, the right side elevational view being a mirror image thereof.
The broken lines in FIG. 3 represent environmental structure (not conventional stitching) and form no part of the claimed design.
